UNITED STATES PATENT OFFICE.

HIRAM BLOOD, OF EAST CAMBRIDGE, MASSACHUSETTS, ASSIGNOR TO HIMSELF AND LORENZO H. DALE, OF SAME PLACE.

LINK-BOX FOR STEAM-ENGINES.

SPECIFICATION forming part of Letters Patent No. 278,766, dated June 5, 1883.

Application filed March 14, 1883. (No model.)

To all whom it may concern:

Be it known that I, HIRAM BLOOD, a citizen of the United States, residing at East Cambridge, in the county of Middlesex and State 5 of Massachusetts, have invented an Improvement in Link-Boxes for Steam Fire-Engines, of which the following is a full, clear, and exact description, reference being had to the accompanying drawings, making part of this specification, in which—

Figure 1 is a perspective view of the link-box of a steam fire-engine having my improvement applied thereto. Fig. 2 is a transverse vertical section through the center of the 15 same.

The ordinary metallic link-box, which slides in the "cross-head" of a steam fire-engine and receives the wrist-pin of the crank upon the crank-shaft, is objectionable, for the reason that 20 its bearing-surfaces soon become badly worn, owing to the great speed and irregular motion of the box and the unequal strain thereon. It is also heavy and expensive, and its great weight also tends to further increase the wear, while 25 the frequent lubrication required results in a great consumption and waste of oil. Lignum-vita has been employed as a substitute for metal in the construction of these boxes, as it is much lighter and will wear away less rapidly than 30 metal; but this material is also objectionable, as it soon becomes split or checked and warped by the heat resulting from friction and the swelling produced by the action of the oil used in lubricating the bearings. Other varieties 35 of hard wood which are much less liable to split or warp could be used; but these would not present bearing-surfaces capable of resisting the wear to which they would be subjected, and have therefore been hitherto found unsuitable for this purpose.

My invention has for its object to overcome all of these difficulties; and it consists in a link-box for steam fire-engines having its bearing-surfaces composed of rawhide, as hereinafter 45 described, whereby the wear is reduced to a minimum and the heating of the bearings and undue consumption of oil entirely avoided.

In the said drawings, A represents a steam fire-engine link-box of the usual form, and 50 adapted to be secured within the cross-head, to

slide therein in the ordinary manner. This box A, which is made, as usual, in two halves, adapted to be secured together by bolts, is composed of hard wood of such description that it will not readily warp, split, or check. I prefer to use for this purpose bird's-eye maple or beech, which are light, strong, and close-grained; but other woods possessing these characteristics may be used instead.

b c represent the plane bearing-surfaces, 60 which slide in contact with the cross-head, and d represents the circular aperture or bearing, within which fits the wrist-pin of the crank on the crank-shaft of the engine. These bearing-surfaces b c d are all composed of strips or 65 pieces of rawhide e, of suitable thickness, cut to the desired dimensions, and firmly secured to the contiguous surfaces of the box A, to which they are applied, by wooden pegs f, cement, copper nails, or in any other suitable 70 manner.

By thus providing a link-box with bearing-surfaces composed of rawhide its durability is so greatly increased that it will outlast a great number of metallic or wooden boxes as heretofore constructed, and consequently the great loss hitherto occasioned by the necessity of frequently replacing these boxes by new ones is avoided, while the anti-friction properties of rawhide, its cheapness, cleanliness, and its 80 non-liability to evolve heat from friction under excessive speed render a link-box constructed in accordance with my invention of great value, and effect a material saving in the cost of repairs, while much less oil is required for lubrication than formerly, resulting in a further 85 economy in the expense of running the engine. One of the greatest advantages, however, incident to the use of my invention lies in the fact that it enables me to construct a link-box 90 of hard wood of a description not liable to split, check, or warp, and which it has hitherto been found impossible to employ for this purpose, on account of its not being able to properly resist the wear upon its bearing-surfaces, and consequently I am enabled to retain 95 all the advantages incident to the employment of a material much lighter than metal, and at the same time reduce the wear to a minimum,

having practically demonstrated by actual use 100

that the wear of the rawhide surfaces after a severe and long-continued test is hardly appreciable.

I am aware that it is not new to provide 5 journal-boxes with rawhide bearing-pieces, and I am also aware that it is not broadly new to apply rawhide to surfaces as cushioning material, and hence I confine myself to the precise invention set out in my claim.

10 I claim—

A link-box for steam fire-engines having its exterior and interior bearing-surfaces composed of rawhide, substantially as set forth.

Witness my hand this 10th day of March, A. D. 1883.

HIRAM BLOOD.
